WATERPROOF GARMENT

Bernard B. Shulman, Philadelphia, Pa., assignor
to Morris Freedman, Philadelphia, Pa.

Application November 30, 1951, Serial No. 259,153

8 Claims. (Cl. 128—287)

1

My invention relates to waterproof garments and method of making same, and it relates more particularly to fabrication of garments such as baby panties.

Garments of the type to which my invention applies consist generally of a waterproof sheet material which is adapted to be disposed interiorly of the garment, and a generally woven or knitted fabric adapted to be disposed on the exterior side of the garment; means to secure the waterproof interior to the generally woven or knitted fabric exterior; and means to secure the garment in place on the body of the wearer. In some instances, the garment may also include a pocket for holding an absorbent material such as a baby diaper. In garments of this character, as hitherto known, a serious problem has presented itself in that it was not possible to secure the waterproof interior to the generally woven or knitted fabric exterior without penetrating the waterproof sheet material and thereby causing leakage. Thus for instance, stitching the woven or knitted fabric to the waterproof material required the penetration of waterproof material by a needle and the passage of a thread through the hole thus formed, with resultant enlargement of the hole by tensions of the fabric against the stitch when the fabric is in use. The useful life of such garments has thereby been extremely limited.

One object of my invention therefore is to provide a garment of the character described which shall be waterproof and leakproof, and which shall remain thus for the life of the fabric itself.

Another object of my invention is to provide a garment of the character described which shall have a strong union between the waterproof material and the woven or knitted fabric without detracting from the leakproof character of the garment.

A further object of my invention is to provide a method of forming a garment of the character described which shall be efficient and positive in operation and inexpensive to perform.

Other objects of my invention will appear in the more detailed description of my invention, which follows.

For the purpose of illustrating my invention, I have shown in the accompanying drawings forms thereof which are at present preferred by me, since the same have been found in practice to give satisfactory and reliable results, although it is to be understood that the various instrumentalities of which my invention consists can be variously arranged and organized and that

2

my invention is not limited to the precise arrangement and organization of the instrumentalities as herein shown and described.

Referring now to the drawing in which like reference characters indicate like parts.

Figure 1 represents a perspective view of a waterproof garment as the same may be worn on a child, and embodying my invention.

Figure 2 represents a perspective view of the waterproof garment illustrated in Figure 1, laid out in open condition ready for assembly on the wearer, and embodying my invention.

Figure 3 represents an enlarged, perspective and sectional view of a seam portion of a waterproof garment, in one stage of the formation thereof, and embodying my invention.

Figure 4 represents an enlarged sectional and perspective view taken generally along the lines 4—4 of Figure 2, and with the region of the seam shown open for clearer viewing.

Figure 5 represents an enlarged sectional view taken generally along the lines 5—5 of Figure 2, and with the region of the seam shown open for clearer viewing.

Figure 6 represents a vertical, enlarged, sectional schematic view of the die portion of a sealing apparatus, showing the same in sealing operation on sheet materials being used in the formation of a garment in accordance with the method of my invention.

Figure 7 represents a vertical, enlarged sectional view taken generally along the lines 7—7 of Figure 2, and with the region of the seams shown open for clearer viewing.

Figure 8 represents a perspective view of an electronic sealing machine of a kind which is adapted to make the seal used in the method embodying my invention.

Figure 9 represents a perspective view showing one stage in the method of assembling a waterproof garment of modified construction, and embodying my invention.

Figure 10 represents a perspective view showing another stage of forming a garment of modified construction, and embodying my invention.

Figure 11 represents a fragmentary view of a corner portion of a garment of another modified construction, and embodying my invention.

Figure 12 represents an enlarged sectional view taken generally along the lines 12—12 of Figure 11.

Figure 13 represents a perspective view showing one stage of the formation of a garment of a further modified construction, and embodying my invention.

Figure 14 represents another stage of the for-

mation of the garment whose earlier stage of formation is illustrated in Figure 13, and embodying my invention.

Figure 15 represents a further stage of the formation of the garment whose earlier stages of formation are illustrated in Figures 13 and 14.

Figure 16 represents a sectional view, greatly enlarged, taken generally along the lines 16-16 of Figure 15, during one stage in the formation thereof.

Figure 17 represents a vertical sectional view of a sealing device and garment sealing assembly of another modified construction, and embodying my invention.

Figure 18 represents one stage in the formation of a garment of further modified construction, and embodying my invention.

Figure 19 represents another stage of the formation of the garment whose earlier stage of formation is illustrated in Figure 18, and embodying my invention.

Figure 20 represents a further stage of the formation of the garment whose earlier stages of formation are illustrated in Figures 18 and 19, and embodying my invention.

Figure 21 represents a perspective view of one stage in the formation of a garment of another modified construction, and embodying my invention.

Figure 22 represents a vertical sectional view greatly enlarged, showing another stage of the formation of the garment whose earlier stage is illustrated in Figure 21, and embodying my invention.

Figure 23 represents a perspective sectional view of a further stage of the formation of the garment whose earlier stages of formation are illustrated in Figures 21 and 22, and embodying my invention.

For purposes of illustration only, I have shown my invention as applied to a baby pantie, and to one which is adapted to receive and hold a diaper in place; although it is to be understood that my invention may as readily be used in other types or kinds of baby panties, or in garments other than baby panties, but which comprise a waterproof sheet material joined to a mesh fabric such as a woven or knitted sheet material, or joined to a felted fabric such as paper, felted cloth material, or woven fabric substitutes. Where used in this specification therefore, the term "fabric" shall be taken to mean a mesh fabric as hereinabove described, as well as a felted fabric as hereinabove described.

According to my invention I provide a waterproof garment 10 which in this case is illustrated as a baby pantie. In the illustrated embodiment of my invention the garment 10 thus comprises a woven, felted or preferably knitted exterior fabric 11 and a waterproof sheet material interior 12. The waterproof sheet material preferably consists of a vinyl plastic or other desirable thermoplastic sheet. Although my invention may be applied to other garments or to other kinds of baby panties, for purposes of illustration I have shown a form of baby pantie in which pockets are provided for reception and retention of a diaper. Thus, there is provided a bed sheet of vinyl plastic 13 generally coterminous with the fabric 11, and preferably folded pocket strips 14, 15, 16 and 17 disposed at the corners of the sheet 13 and in overlapping relation one with another. The vinyl sheet 13 and mesh or felted fabric 11 each comprises generally an abdomen edge portion 18, a back edge portion 19, a right leg receiving portion 20 and a left leg receiving portion 21, defining

generally a corner portion 14-a between the right leg receiving portion 20 and the back portion 19, a corner portion 15-a between the left leg receiving portion 21 and the back portion 19, a corner portion 16-a between the left leg receiving portion 21 and the abdomen portion 18, and a corner portion 17-a between the right leg receiving portion 20 and the abdomen portion 18. If desired, suitable fasteners such for instance as snap fastener male members 22 may be disposed on or through the fabrics intermediate the leg receiving portions 20, 21 and the back edge portion 19; and snap fastener female members 23 may be disposed on or through the fabrics in corresponding portions of the garment intermediate the abdomen edge portion 18 and the leg receiving portions 20, 21; all of said snap-fastener members 22 and 23 being preferably in proximity to the edge portions of the fabric intermediate leg portions 20, 21 and the upper edge portions 18 and 19.

The folded pocket strips 14, 15, 16 and 17 preferably each respectively comprises a single sheet of vinyl plastic or other suitable thermoplastic folded as at 24, lapped upon itself and laid generally upon one corner portion of the bed sheet 13. It is to be understood however, that my invention is not limited to the use of a folded pocket strip, but will also work when a single sheet, unfolded strip (not shown) is used, having substantially the same marginal shape and marginal dimensions as the folded pocket strips. The folded strips 14, 15, 16 and 17 are therefore to be considered merely illustrative. The marginal portions 25 and 26 of each of the strips 14, 15, 16 and 17 is cut or otherwise formed to be substantially co-terminal with the edges of the bed sheet 13 in each of the respective corners 14-a, 15-a, 16-a and 17-a of said bed sheet 13 on which said strip is adapted to be laid. The folds or diagonal portions 24 of each of the strips 14, 15, 16 and 17 are of a length greater than the distance between the median of the leg portions 20 or 21 and the median of the abdomen edge portion 18 or the back edge portion 19; and the end portions of the folded strips 14, 15, 16 and 17, adjacent the folds or diagonal portions 24 thereof, are preferably alternately overlapped one upon another as at 27, 28, 29 and 30, respectively.

An elastic band 31 of any suitable elastic material such as rubber, rubberized fabric or the like, may be used, and in such event is stretched across preferably the back edge portion 19 of the fabric 11 and is secured thereto by any suitable means such as stitches 32.

An initial or primary sealing seam 33 is preferably formed adjacent the edges 18, 19, 20 and 21, as well as along the edges 34 of the side portions intermediate the leg portions 20, 21 and the abdomen portion 18, and the side portions 35 intermediate said leg portions 20, 21 and the back portion 19. In one embodiment of my invention, a secondary sealing seam 36 is formed intermediate the primary sealing seam 33 and the exposed portion 37 of the bed sheet 13; and in such event the secondary seam 36 is preferably disposed closely adjacent the primary seam 33. The primary seam 33 and the secondary seam 36 are so constructed and so disposed as to have certain characteristics which will be more clearly understood following a description of the manufacture and assembling of the garment 10, which follows:

The garment 10 is preferably made by cutting out the pocket strips 14, 15, 16 and 17, the bed sheet 13 and the mesh fabric sheet 11 according

to their respective patterns, which patterns are formed in accordance with the foregoing description of the garment 10; preferably securing the elastic 31 to the back edge portion 19 of the fabric 11 by any suitable means such as the stitches 32 and then assembling the fabrics 11, sheet 13 and pocket strips 14, 15, 16 and 17 in one of the following manners: In the embodiment of my invention illustrated in Figures 1 to 6 inclusive, the sheets are laid one upon another in the following order: the bed sheet 13 is laid first, as may be seen in Figure 3 which illustrates the manner of forming the edge portion 35. The fabric sheet 11 is then laid upon the bed sheet 13 with the respective edges 38 and 39 co-terminous. The folded pocket strip 15 is then laid upon the fabric sheet 11 with the edges 25 and 26 of the strip co-terminous with the respective edges 39 and 38 of the bed sheet 13 and the mesh fabric 11.

Dies 40 and 41, preferably of an electronic plastic sealing device, are then brought to bear upon the sheet pile 42 thus formed. The die 40 consists preferably of a flat platen; and the die 41 consists preferably of a flange downwardly projecting from an electronic heat sealing device 44. The die 41 preferably has a bottom edge substantially parallel to the platen 40, and substantially vertical parallel edges upwardly extending from said bottom edge and spaced a distance substantially equal to the widths of the seam 33 or 36. The die 41 is preferably formed along the same shape or path as the seam 33 or 36. If desired however, it may be formed of a segment or segments of said path, and successive impressions made to complete said path, in place of the unitary impression hereinafter described.

In a preferred form, the pile 42 is laid on the die platen 40 with the edges 18, 19, 20, 21, 34 and 35 substantially parallel to corresponding portions of the die 41, and said die 41 in substantial registry with the desired location of the initial or primary seam 33. The die 41 is then advanced downwardly and brought to bear against the pile 42. In this position, the die 41 is preferably immediately adjacent the edges 18, 19, 20, 21, 34 and 35. Downward pressure is then brought to bear through the die 41 against the pile 42 and the platen die 40, and at the same time heat is interposed between the dies by any suitable means such for instance as high frequency current generated by the electronic device 44, until the vinyl plastic intermediate the dies 40 and 41 is melted and the plastic thus molten is forced through and among the fibers of the fabric 11. Suitable controls (not shown) in the electronic sealing device 44 of which the dies 40 and 41 are a part, maintain the heat and pressure within the required and safe degrees for operation to reduce the plastic to a molten state and to cause it to permeate the fabric 11, while preventing the molten plastic from flowing away from the seam 33, separating from the sheets, or being pressed to too thin a degree of seam. When the permeation is substantially complete, heat is preferably reduced substantially to room temperature while the dies remain substantially in place. After the seam has itself cooled substantially to room temperature, the dies 40 and 41 are separated and the pile 42 is withdrawn.

It will be found that there has been thus formed a seam composed of homogeneous vinyl plastic 43 through which has been interthreaded the fibers of a mesh or felted fabric, and said homo-

geneous plastic 43 is itself integral with the plastic sheets 13 and 15. In this condition, the fabric serves to reinforce the thermoplastic, while the cooled thermoplastic serves to cement the fabric to the seam. The seam 33 thus formed is waterproof, and stronger than any of the sheets of which it is formed. Moreover, tensile strains imposed thereon will not serve to separate it or to disturb its waterproof character. Indeed, actual tests have shown that the sheets joined by the seam 33, when under sufficient abnormal strain or stress will themselves be torn before the seam 33 would be broken.

In one embodiment of my invention, as illustrated in Figures 2, 4 and 5, the sheets forming the pile 42 are separated interiorly of the seam 33 after said seam is formed, and the pocket strips 14, 15, 16 and 17 are folded upwardly and backwardly over the edge portion 35, and the fabric sheet 11 and bed sheet 13 are folded downwardly and backwardly beneath the edge portion 35, revealing a rounded edge portion 45 of the garment 10. The secondary seam 36 is then formed by placing the garment pile between the dies 40 and 41 (when the die 41 is discontinuous about the seam to be formed), or between the die 40 and a die (not shown) similar to the die 41 but whose outline dimensions are slightly smaller than those of the die 41. In either event, the seam 36 is formed by a procedure substantially similar to that used in forming the seal 33 but the seam 36 is preferably disposed immediately adjacent the interior edges 25, 26, 38 and 39 which are now disposed intermediate the pocket strips 14, 15, 16, 17 and the bed sheet 13 and fabric 11. By this means, the fabric 11 is again permeated by thermoplastic and serves to reinforce the seam 36. Not only so, but a pocket 46 is formed between the bed sheet 13 and the pocket strips 14, 15, 16 and 17 interiorly of the seam 36. This pocket 46 is of waterproof construction for the molten plastic of the seam 36 has sealed off the outer marginal spaces between the pocket strips 14, 15, 16 and 17 and the bed sheet 13. There is thus formed a continuous plastic surface, interior of the pocket 46 and composed of the undersurface 47 of the pocket strips 14, 15, 16 and 17, the plastic juncture 48 formed by the seam 36, and the upper surface 49 of the bed sheet 13. It will thus be found that there has been formed not only a strong union between the plastic elements and the fabric 11 in the initial or primary seam 33, with a rounded and neatly formed edge portion 45 but a waterproof pocket 46 for retention of an absorbent pad such as a diaper 50.

In Figures 9 and 10 are illustrated a modified construction embodying my invention. In this construction, a pile 51 of sheet materials 13, 11, 14, 15, 16 and 17 is laid on the platen 40 for sealing, the laying being in the following order: the bed sheet 13 is laid on the bottom. The fabric sheet 11 is laid on the bed sheet 13 in registry with said sheet 13. The pocket strips 14 and 15 are laid on the fabric 11 in converse order with the manner of laying said strips in the modification illustrated in Figure 2; and the pocket strips 16 and 17 are laid on the fabric 11 and inlapping relation to the ends of the pocket strips 14 and 15, and in converse position to that shown in the modification illustrated in Figure 2. The outer edges of the pocket strips 14, 15, 16, 17 are in registry with the fabric 11.

The die 41 is lowered and brought to bear against the pile 51 in proximity to the outer edge 52 thereof, and an initial or primary seal

53 is electronically imparted to the sheets of the pile 51, melting the plastic between the dies 40 and 41, permeating the fabric 11 therebetween, and forming when cooled a homogeneous plastic mass reinforced by the fabric 11 therein. The corners defined by the pocket strips 14, 15, 16 and 17 are then turned inside out by placing the hand within the pocket 54 intermediate the pocket strips 14, 15, 16 and 17 and the fabric 11, grasping the interior of the pocket and folding each of the pocket strips 14, 15, 16 and 17 about the outer edge 52, substantially as is shown in Figure 10 until the pocket strips 14, 15, 16 and 17 are lapped against the underside of the bed sheet 13 instead of against the upper face of the fabric 11. When the pile 51 is then turned down-side-up, it will present an appearance substantially similar to that of the pile in Figure 2. If desired, a secondary seam 36 may then be formed in a manner similar to that described and shown for the modification illustrated in Figure 2.

In Figures 11 and 12 is illustrated another modified construction embodying my invention. In this construction, a pile 55 of sheet material is formed by laying the fabric sheet 11 on the bottom, the bed sheet 13 on the fabric sheet 11 and in registry therewith, and the pocket strips on the bed sheet 13 in substantially the same manner as said strips are illustrated as being laid thereon in Figure 2. The pile thus formed is laid on the platen 40 and a die similar to the die 41 brought to bear thereupon to form the seal 56 in substantial juxtaposition to the outer edge 57 forming the periphery of the pile 55. In this construction, the seal 56 serves to unite all of the sheets together in one waterproof and reinforced seal. No rolled edge is used in this modification, and if desired, a secondary seal may be dispensed with.

In Figures 13 to 16 inclusive, is illustrated another modified construction and method embodying my invention. According to this construction and method, I lay the bed sheet 13 on the platen 40, and lay the fabric sheet 11 on, and in registry with, the bed sheet 13. Weld strips 58 are laid on the edge portions 59 preferably intermediate the leg receiving portions 20, 21 and the back edge portion 19. The weld strips 58 consist preferably of sheet thermoplastic, preferably of the same kind as that of which the bed sheet 13 is made. A die (not shown) substantially similar to the die 41, but without a die segment adjacent the back edge portion 19, is mounted in the electronic device 44 in a manner similar to the mounting of the die 41, and is lowered until it bears against the pile 60 formed by the plastic sheet 13, fabric 11 and weld strips 58. Operating the electronic device in substantially the same manner as hereinbefore described, a seam 61 is formed adjacent the edge portion 59 of the pile 60 throughout the periphery of the pile 60 with the exception of the back portion 19. This seam 61, in that portion thereof which is not formed through the weld strips 58, consists of a thermoplastic seal having one surface thereof reinforced with fabric 11. At the weld strip portion 62 of the seam 61, however, the seam consists of a plastic seal having the center thereof reinforced with the fabric 11; and said fabric 11 is accordingly locked in the seal 62 between the completely plastic exteriors thereof. In this manner, it is impossible for the fabric 11 to be torn from the plastic sheets 13 and 58, at the beginning of the seam 61.

The hand 63 is then inserted in the pile 60 75

between the sheet 11 and sheet 13 until it reaches the abdominal edge portion 18 whereupon it grasps said portion and turns the pile 60 inside out substantially as is shown in Figure 14. In this condition, the edge portion 59 will be found to have been turned inwardly, substantially as is shown in Figure 16, leaving an outer rolled edge 64 throughout the pile, with the exception of the back edge portion 19.

The pile 60 is then turned down-side-up, so that the fabric 11 is at the bottom and the bed waterproof sheet 13 is at the top. Pocket strips 14, 15, 16 and 17 are then placed on the sheet 13 in substantially the same manner as is illustrated in Figure 2. If desired, and preferably prior to said placing of the pocket strips, a non-absorbent and non-thermoplastic insert sheet 65 may be inserted between the thermoplastic sheet 13 and the fabric 11 in regions thereof which are intended to be disposed between the dies 40 and 41 during the next sealing operation. The insert sheet 65 may if desired consist of fiberboard, mica or other suitable substance. The pile 60, with its inserts if they are used, and with the pocket strips 14, 15, 16 and 17 placed in position thereon, is positioned on the platen 40 beneath an appropriate die such as the die 41, and the electronic apparatus 44 is then operated, substantially as hereinbefore described, to form the seal 66 adjacent the edges 64, and spaced a suitable distance from the back edge portion 19. The distance between the seal 66 and the edge 19 may be determined by the size and position of the material used for drawing the waistline together, when said material is used in the back edge portion 19. Such material is illustrated for instance in Figures 2 and 5, and in the latter figure is indicated as the elastic 31 sewed or otherwise secured to the fabric 11. In the sealing operation, it will be found that the pocket strips 14, 15, 16 and 17 are respectively merged with one another at the overlapping regions 27, 28, 29 and 30, and with the waterproof bed sheet 13, operatively to form a unitary and continuous inside wall 46 of a pocket for holding a diaper or other suitable absorbent material, substantially as has been hitherto described with respect to other modifications of my invention; but in this instance, the seal 66 does not penetrate to the fabric 11 because of the use of the insert or inserts 65; and the fabric 11 is thus rendered free of the appearance of thermoplastic on its outside surface. After sealing, the insert or inserts 65 may be withdrawn through the opening at the back edge portion 19, and the fabric 11 may be joined at said back edge portion 19 to the thermoplastic sheets by any suitable means such as the stitching 67 which may also be used as ornamental stitching throughout the rest of the edge portion of the garment. It will be found that by my novel construction, the ornamental stitching 11 does not disturb the waterproof construction of the pocket interior 46. In a preferred form of ornamental stitching 11, the stitches are passed through the primary seal 61 and serve further to hold the fabric 11 thereagainst at the rolled edge portion 64.

In Figure 17 is illustrated another modified construction embodying my invention. Herein, internal wedge dies schematically shown at 68 and 69 are used to cooperate with an external wedge die schematically shown at 70, to form a rolled edge seal in one operation. In this method and construction, internal wedge dies 68 and 69 are provided having parallel exterior surfaces 71,

and parallel interior surfaces 72. The rearward edges of the dies 68 and 69 are preferably inwardly inclined toward each other as at 73. The external die 70 is preferably formed with a wedge-shaped forward edge portion 74 having inclined faces 15 which are respectively preferably parallel to the rearward inclined edges 73 of the internal dies 68 and 69.

The internal dies 68 and 69 are spaced from each other a suitable distance and the pocket strips such as the strip 15 are laid on the exterior face 71 of the die 68, with their outer edge portions 16 draped over the rearward edge portion 77 of the die 68 a suitable distance.

The fabric 11 is laid in position on a suitable table and the waterproof bed sheet 13 is laid on the fabric 11 and in registry therewith. The die 69 is then placed on the sheet 13 with its edges 73 substantially parallel to the edges of the sheet 13, but spaced therefrom a suitable distance so that the registering edge portions 78 of the fabric 11 and sheet 13 extend outwardly from the end 79 of the die 69 a distance substantially equal to the spacing between the edge portion 76 and the end portion 77 of the die 68. The outwardly extending portions 80 of the registering sheet 13 and the fabric 11 are then smoothly laid on the inclined face 73 and interior surface 72 of the die 69; and the overhanging portions 81 of the pocket strips 14, 15, 16 and 17 are smoothly laid against the inclined face 73 and interior surface of the die 68; and the edge portion 76 of said pocket strips are placed on the edge portions 78 and in registry therewith. In this manner, the die and sheet assemblies will appear substantially as is illustrated in Figure 17. The dies 68, 69 and 70 are then connected with an electronic device such as the device 44 with the dies 68 and 69 respectively connected in the same manner as the dies 41 and 40. The die 70 is advanced toward the dies 68 and 69 until it holds the respective strips smoothly against the inclined faces 73 of the internal dies. When the device 44 is then electronically operated, a seal will be formed between the dies 68 and 69. Upon withdrawal of the dies from the sheets, it will be found that a rolled edge has been established with an electronic seal internally formed therein, and all in one operation. This method may be used in any portion of the garment, or in all portions of the garment with the exception of any desired opening such for instance as the back edge portion 19 which may be intentionally left open for the purpose of withdrawing the dies 68 and 69 therethrough. Such opening may thereafter be closed by any suitable means, such for instance as hereinbefore described.

In Figures 18 to 20 inclusive is illustrated a further modified construction and method embodying my invention. Herein, the pocket strips 14, 15, 16 and 17, as for instance the pocket strip 15, are laid on the waterproof bed sheet 13 in substantially the same manner as is illustrated in Figure 2, and disposed between dies such as the dies 40 and 41 of the electronic device 44, and the electronic device operated so that a seal 81 is formed therebetween, substantially along the same lines, and preferably in the same position as the seal 66 as illustrated in Figures 15 and 16. In this manner, the waterproof interior of the pocket is first established. The fabric 11 is then laid on the pile 82 thus formed, and with its outer edge substantially in registry with the outer edge of the pile 82. The electronic device 44 is then operated to establish a secondary seal 83

between the fabric 11 and all of the sheets of the pile 82 in the outer edge portion 84 of the pile 82 between the seal 81 and the extreme outer edge 85 of said pile 82. This secondary seal 83 comprises a homogeneous thermoplastic base portion reinforced by the fabric 11 adjacent its upper surface. The pile 82 with the fabric 11 thus secured thereto is then turned inside out through any desired opening as has been hitherto described, and the pile turned down-side-up so that the fabric 11 becomes disposed on the under side of the pile 82, substantially as is illustrated in Figure 20. By so doing, a rolled edge 86 is formed between the fabric 11 and the outer edge portion 84 of the pile 82, with the extreme edge 85 disposed interiorly of the garment. If desired, the fabric 11 may be drawn against the secondary seal portion 83 by any suitable means such as the ornamental stitching 87.

In Figures 21 to 23, inclusive, are illustrated another modified construction and method embodying my invention. Herein the sheets and pocket strips are made oversize, and a pile 88 is formed by laying the fabric sheet 11-b on the bottom, laying the waterproof bed sheet 13-b thereon and in registry therewith, and laying the pocket strips 14-b, 15-b, 16-b and 17-b on the bed sheet 13-b in substantially the same manner as the pocket strips 14, 15, 16 and 17 respectively are illustrated as being laid on the sheet 13 of Figure 2.

The electronic device 44 is equipped with a platen die 40 and a cutting electronic die 89 comprising an electronic transmitting element such as is schematically shown at 90 substantially similar in electronic construction to the die 41, and a knife edge cutting element 91 downwardly projecting from the electronic element portion 90 and along the outer edge thereof. The die 89 may be formed in the same configuration as the seam desired to be established, and the cutting die 91 is preferably formed along the desired periphery of the garment being made.

The pile 88 is placed on the platen die 40 of an electronic device 44 in the desired location with respect to the knife edge 91, and the cutting electronic die 89 is borne downwardly against the pile 88, cutting away the undesired material 92 and at the same time bearing against the outer edge portion of the pile 88 while heat-welding the elements thereof together into the reinforced plastic seam 93. When the seam 93 is cooled and the die 89 is withdrawn, it will be found that the garment has been formed in one operation, with the pocket elements sealed so as to form a continuous waterproof interior 46, and with the fabric 11-b secured to the sealed edge 93 by the plastic thereof permeating said fabric. If desired, ornamental stitching 94 may be used on the seal 93, and in such event, it will serve the further purpose of locking the fabric 11-b within the seal 93 against any tendency to be removed therefrom by such action as a pealing action.

In any of the modifications of my invention, it is to be understood that the garment may be provided with any desired attaching means, and the snap fastener devices shown in Figures 2 and 11 are merely illustrative. Moreover, if desired, suitable reinforcing means such for instance as tape (not shown) may be used between the sheet elements of the garment or external of the sheet elements, for any desired purpose, and when so used may be either plastic-seamed as hereinabove described with respect to the fabric, or held in position by any other suitable means, as desired.

11

Moreover, the plastic-seaming operation may be enhanced by wetting the fibers of the fabric 11 with a suitable liquid or emulsified plastic. Thus, for instance, when it is desired to form a plastic seam between the fabric 11 and the sheet 13, the sheet 13 may be laid on the platen 40, and the fabric 11 laid on the sheet 13. The liquid or emulsified plastic may then be spread on the fabric 11 in the region of the desired seam (not shown), and the die 41 brought to bear upon the pile (not shown) thus formed. When the dies 40 and 41 are electronically operated as hereinbefore described, the volatile element will be driven from the liquid plastic where that is used; or the emulsifying agent will be broken down and the liquid ingredient driven off from the emulsified plastic, where that is used. In either event, the plastic itself will melt and combine with the molten plastic of the sheet 13 in permeating the fibers of the fabric 11 and forming a plastic coat on the upper surface thereof, thereby to aid in locking the fabric 11 in the plastic seam thus being formed.

It is to be understood, that any of the elements shown in any of the foregoing modifications, whether as to construction, or method, may be used as desired, interchangeably with other elements of method or construction shown in the other modifications, without departing from the spirit or essential attributes of my invention.

It will thus be found that by my novel construction and method, I have formed a garment which is capable of holding an absorbent material which will retain said material and all of its liquid contents in a waterproof manner, and whose seams are leakproof regardless of the stresses or strains imposed on the garment.

I am aware that the invention may be embodied in other specific forms without departing from the spirit or essential attributes thereof, and I therefore desire the present embodiments to be considered in all respects as illustrative and not restrictive, reference being had to the appended claims rather than to the foregoing description to indicate the scope of the invention.

Having thus described my invention, what I claim as new and desire to secure by Letters Patent is:

1. A garment comprising a pile assembly composed of a thermoplastic sheet, a fabric sheet, and a thermoplastic pocket strip; said pile assembly comprising an abdominal portion, a back portion, right leg portion, and left leg portion; said thermoplastic sheet, fabric sheet and thermoplastic pocket strip comprising substantially registering edges; said edges being united in a unitary thermoplastic weld through which said fabric passes in thermoplastic-permeated state while reinforcing said weld with fibers of said fabric.

2. A garment comprising a pile assembly composed of a fabric sheet, a thermoplastic sheet, and thermoplastic pocket strips; said pile assembly having a right leg portion, a left leg portion, an abdominal portion and a back portion; said sheets and at least one of said strips having substantially registering edge portions; said edge portions comprising a thermoplastic weld through which said fabric extends in thermoplastic-permeated condition while the fibers of said fabric in said weld are in weld-reinforcing relation to said weld; said weld being disposed interiorly of said pile, with the pocket strips being folded away from said weld in one direction, and said sheets being folded away from said weld in another direction, operatively to form a rolled

12

edge; and said strip and said sheets being thermoplastically united in a secondary weld disposed in said pile interiorly of said first-mentioned weld; said secondary weld comprising a unitary thermoplastic weld through a portion of which said fabric passes in thermoplastic-permeated condition, and said secondary weld forming with said pocket strips and said thermoplastic sheet a waterproof, substantially continuous and unbroken interior pocket face.

5 3. A garment comprising a pile assembly composed of a fabric sheet, a thermoplastic sheet, and thermoplastic pocket strips; said pile assembly having a right leg portion, a left leg portion, an abdominal portion and a back portion; said sheets and at least one of said strips having substantially registering edge portions; said edge portions comprising a thermoplastic weld through which said fabric extends in thermoplastic-permeated condition while the fibers of said fabric in said weld are in weld-reinforcing relation to said weld; said weld being disposed interiorly of said pile, with the pocket strip being folded away from said weld in one direction, and said sheets being folded away from said weld in another direction, operatively to form a rolled edge; and said strip and said thermoplastic sheet being thermoplastically united in a secondary weld disposed in said pile interiorly of said first-mentioned weld; said secondary weld forming with said pocket strip and said thermoplastic sheet a waterproof, substantially continuous and unbroken interior pocket face.

20 4. A garment comprising a pile assembly composed of a thermoplastic sheet, a fabric sheet, and a thermoplastic pocket strip; said pile assembly comprising an abdominal portion, a back portion, right leg portion, and left leg portion; said thermoplastic sheet, fabric sheet and thermoplastic pocket strip comprising substantially registering edges; said edges being united in a unitary thermoplastic weld through which said fabric passes in thermoplastic-permeated state while reinforcing said weld with fibers of said fabric; said weld being disposed inwardly of the edge of said pile, with at least one of said sheets extending outwardly and away from said weld in one direction, and said pocket strip extending outwardly and away from said weld in another direction, said sheet and said pocket strip being disposed in substantially lapped relation to each other interiorly of said garment's edges with the weld disposed intermediate said lapped disposition and said edges.

25 5. A garment comprising a pile assembly composed of a thermoplastic sheet, a fabric sheet, and a thermoplastic pocket strip; said thermoplastic sheet, fabric sheet and thermoplastic pocket strip comprising substantially registering edges; said edges being united in a unitary thermoplastic weld through which said fabric passes in thermoplastic-permeated state while reinforcing said weld with fibers of said fabric; said weld forming with said pocket strip and said thermoplastic sheet a waterproof, substantially continuous and unbroken interior pocket face.

30 6. A garment comprising a pile assembly composed of a fabric sheet, a thermoplastic sheet, and thermoplastic pocket strips; said pile assembly having a right leg portion, a left leg portion, an abdominal portion and a back portion; said sheets having substantially registering edge portions united one to another; and said strip and said thermoplastic sheet being thermoplastically united in a weld disposed in said pile interiorly

of said edge portions; said weld forming with said pocket strip and said thermoplastic sheet a waterproof, substantially continuous and unbroken interior pocket face.

7. A garment comprising a pile assembly composed of a fabric sheet, a thermoplastic sheet, and thermoplastic pocket strips; said pile assembly having a right leg portion, a left leg portion, an abdominal portion and a back portion; said sheets and at least one of said strips having substantially registering edge portions; said edge portions comprising a thermoplastic weld through which said fabric extends in thermoplastic-permeated condition while the fibers of said fabric in said weld are in weld-reinforcing relation to said weld; said weld being disposed interiorly of said pile, with the pocket strip being folded away from said weld in one direction, and said sheets being folded away from said weld in another direction, operatively to form a rolled edge; and said strip and said thermoplastic sheet being thermoplastically united in a secondary weld disposed in said pile interiorly of said first-mentioned weld; said fabric sheet being secured to said thermoplastic sheet between said rolled edge and the interior of said garment; and said secondary weld forming with said pocket strip and said thermoplastic sheet a waterproof, substantially continuous and unbroken interior pocket face.

8. A garment comprising a pile assembly composed of a fabric sheet, a thermoplastic sheet, and at least one thermoplastic pocket strip; said thermoplastic sheet being disposed on said fabric sheet; the edges of said thermoplastic sheet being substantially in registry with the edges of said fabric sheet; said pocket strip being disposed on said thermoplastic sheet; a thermoplastic weld between said pocket strip and said thermoplastic sheet and defining the outline of at least a portion of a pocket; said weld forming with said pocket strip and said thermoplastic sheet a waterproof, substantially continuous and unbroken interior pocket face; and said fabric sheet being united to said thermoplastic sheet in proximity to the edges thereof.

BERNARD B. SHULMAN.
